UNITED STATES PATENT OFFICE.

JULIUS SAX, OF BEDFORD SQUARE, COUNTY OF MIDDLESEX, ENGLAND.

SIGNALING DEVICE.

SPECIFICATION forming part of Letters Patent No. 391,276, dated October 16, 1888.

Application filed July 30, 1888. Serial No. 281,379. (No model.) Patented in England June 12, 1888, No. 8,644.

To all whom it may concern:

Be it known that I, JULIUS SAX, a subject of the Queen of Great Britain and Ireland, residing at 7 Ridgmount Street, Bedford Square, in the county of Middlesex, England, electrical engineer, have invented a certain improved apparatus or appliance especially adapted for communicating between drivers and passengers in vehicles, but applicable 10 also to other analogous purposes, (for which I have applied for a patent in Great Britain, No. 8,644, dated June 12, 1888,) of which the following is a specification.

The object of my invention is to provide a 15 simple and efficient appliance for communicating between the driver and passenger in a cab or other vehicle, or for other purposes of communication, which apparatus is free from dependence upon mechanical locking or releasing, and is therefore especially adapted 20 for situations wherein there is motion or vibration.

The apparatus or appliance constructed according to my invention is operated entirely 25 by electricity, and the moving parts are by magnetic attraction maintained in the positions to which they are brought. I employ for this purpose a permanent magnet, with its two poles in proximity to the pole of an 30 electro-magnet. I mount or center upon the pole of the electro-magnet a truly-balanced disk or moving part, with a soft-iron armature attached to it and in magnetic contact with the core of the electro-magnet. This 35 soft-iron armature, when brought into the neighborhood of either of the poles of the permanent magnet, is attracted and held in position thereby. The disk or moving part is marked with the necessary indication, and 40 a portion of it is exposed at an aperture through the casing, so that when the disk is in one position there is no indication; but when it is brought into the other position the word or information which it is wished to 45 convey is exposed. The disk or moving part is operated by passing a current round the coils of the electro-magnet in one direction for indicating and in the other direction for removing the indication. Suppose the armature or disk is in the position with its armature retained by the magnetic attraction of 50 one of the poles of the permanent magnet, and

that a blank part of the disk or moving piece is exposed at the aperture. When the indication is required to be given, the electro-magnet is magnetized by a current passed in such a direction that the armature of the disk or moving piece is repelled from the pole of the permanent magnet by which it was held, so that the armature moves round until it 60 comes within the influence of the opposite pole of the permanent magnet, when it is held thereby, and in this position the requisite word or indication is exposed at the aperture. To release the indication and return the disk 65 or movable piece to its non-indicating position, the electro-magnet is magnetized by a current of the reverse direction to that previously sent through, and by this the armature is repelled from the pole by which it was 70 held to expose the indication, and the disk or movable piece rotates or moves until the armature comes within the influence of the other pole of the permanent magnet, by which it is again held in its non-indicating position. 75 There may be one or any number of these devices combined in one instrument, in accordance with the number of indications to be given, and in that case there may be one releasing-circuit common to them all. There 80 may be combined in the circuits a bell or other signaling device to draw attention to the indication.

In order that my said invention may be 85 fully understood, I shall now proceed more particularly to describe the same, and for that purpose shall refer to the several figures on the annexed sheet of drawings, the same letters of reference indicating corresponding parts in all the figures.

Figure 1 is a face view of a casing containing 90 an apparatus arranged according to my invention. Fig. 2 is a transverse section of the same, and Fig. 3 is a plan with the top of the casing removed. Fig. 4 is a side elevation, and Fig. 95 5 a vertical section, of one of the disk-operating devices, the others being similarly arranged or constructed. Fig. 6 is a plan of the same with the disk in position, and Fig. 7 is a plan with the disk removed. Fig. 8 is a 100 plan of under side of the disk. Fig. 9 is a diagram showing the arrangement of the wires, battery, and bell in connection with the apparatus for operating it.

A is the casing, having in its under side a hole, a_1 , for the passage of the conducting-wires, and a glass top, B, covering the upper plate, a_2 , of the casing, in which apertures a^3 are made, at which are exposed the markings on the disks. The glass B is secured by a screw-ring, c, with rubber packings at a^4 to prevent the entrance of wet.

In the casing A are fixed the disk-operating devices, each of which is constructed or arranged as follows: d is the core of an electro-magnet, D, secured to the bottom of the casing.

E is a permanent magnet with its poles $e\ e'$ projecting above the non-magnetic plate f, which also encircles the core d of the electro-magnet and serves as a means of retaining the magnets in position. The projecting poles $e\ e'$ are formed by screws passing through the plate 20 f and screwed into the ends of the magnet E, and serving also to secure the stops $e^2\ e^3$. The top of the core d of the electro-magnet D is recessed to receive a pivot, d^2 , upon which rests the cup g in the center of the disk G.

g^2 is a soft-iron armature fixed to the disk G, it surrounding the cup g and extending radially to one side. It is provided with a stop, g^3 , and is balanced by a non-magnetic strip, g^4 , extending in line with the armature g^2 . The disk G is thus balanced. The said disk is marked with the required word or indication in such a position that when the stop g^3 is against the stop e^2 the word or indication is not exposed at the aperture a^3 ; but when the stop g^3 bears against the stop e^3 the said word or indication is exposed at the said aperture. The inward part of the strip g^4 , surrounding the cup g, is over the end of the core d and in such close proximity to it that when the core 40 is magnetized the said strip g^4 is magnetized with the same polarity as that of the said end of the core d.

The electro-magnet D is wound with two coils, d^3 and d^4 , all the coils d^3 of the disk-actuating devices being in multiple arc from the circuit j to and from a battery, H, there being a bell, I, in the circuit. The circuits through one or the other of the coils d^3 can be completed by a switch or push-button, d^5 . The coils d^4 are connected in series with a circuit, k, to and from the battery H, which circuit can be completed by a switch or push-button at k^2 . The coils d^3 and d^4 are so arranged that they respectively have a current in reverse 55 directions sent through them when their circuits are completed—that is to say, the coils d^3 have a current in one direction and the coils d^4 have a current in the opposite direction. Thus the poles of the cores d of the electro-magnet D are magnetized, so that they have a polarity of one denomination when a current is sent through the circuit j and of the opposite denomination when a current is sent through the circuit k.

65 The armatures g^2 of the disks G, when no current is sent through the electro-magnet D,

are attracted by that one of the poles $e\ e'$ in whose neighborhood they are. Suppose that the disks G are marked, respectively, with the words "left," "right," "speak," and "stop," 70 and that when the stops g^3 rest against the stops e^3 , (owing to the armatures g^2 being attracted by the pole e' of the permanent magnet,) the required indication is given by completing by means of the button d^5 the circuit 75 of that one of the coils d^3 which encircles the core d under the disk, having marked on it the word which is required to be exhibited, so that a current from the battery H is sent through the said coil d^3 in such a direction that 80 the upper end of the core d is magnetized with a polarity the same as that of the pole e' of the permanent magnet E, and the armature g^2 is similarly magnetized, and consequently it is repelled from the pole e' and attracted by the 85 pole e , and the disk partially rotates until the stop g^3 comes against the stop e^2 and is, after the button d^5 is released, retained in this position by the attraction of the said pole e of the permanent magnet E. In this position of the disk 90 the required word or indication is exposed at the aperture a^3 therefor in the plate a_2 of the casing. Similarly the words on either of the disks can be exposed at their apertures by pressing the button d^5 to complete the circuit 95 through the coil of either of the electro-magnets under the disk to be operated. To release the disk and cause a blank part of the disk to again come opposite the aperture a^3 , the button k^2 is pressed, so that a current is 100 sent through the coils d^4 in a direction the reverse of that previously sent through the coils d^3 , and so the armature g^2 , through the core d, is magnetized with a polarity of the same denomination as that of the pole e of the electro-magnet E, and the said armature is repelled from the pole e and attracted to the pole e' , the stop g^3 coming to rest against the stop e^3 , and when the button k^2 is released the attraction 105 by the pole e' of the armature retains the disk 110 in the position to which it has been brought, and in this position the word or indication is not seen at the aperture a^3 . All the coils d^4 being in one circuit, the operation of the button k^2 releases and returns to their non-indicating 115 positions all the disks which may be in an indicating position. The coils d^3 not being in series, that one only of the disks which it is desired to operate is moved when the button d^5 completes the circuit through the coil of the 120 electro-magnet under that particular disk. The bell I sounds when an indication is given, as it is included in the circuit j.

It is to be understood that there may be one or any number of disks with actuating devices, as described, and that they may be marked in any desired way to make any required indication or convey any desired order or information, such as may be necessary on vehicles or vessels, or in other places where the apparatus is used. I have shown a circular casing; but it will be evident that the casing may be 125

of other convenient shape, and that the other details may be varied without departing from the nature of my invention.

Having now particularly described and ascertained the nature of my said invention and in what manner the same is to be performed, I declare that what I claim is—

1. In an apparatus or appliance for communicating orders or information from one place to another, the combination of a disk or movable piece provided with an armature, as described, a permanent magnet by which said disk is retained in one or the other of the two positions to which it may be brought, and an electro-magnet by which, when excited or energized, the disk can be moved from said position, substantially as and for the purposes set forth.

2. The combination of the electro-magnet, the permanent magnet, and the balanced disk mounted upon the core of the electro-magnet and provided with an armature normally attracted by one or the other of the poles of the permanent magnet, and repelled from the one

pole and attracted to the other pole of said permanent magnet by the alternation of polarity of the core of the electro-magnet, substantially as and for the purposes set forth.

3. The combination of a plurality of disks, each provided with an armature and an electro-magnet and a permanent magnet for each disk arranged with relation to said disk and its armature, in the manner hereinbefore indicated, a battery and circuit connection, whereby each disk can be operated separately to bring it to indicating position, while all of the disks can be operated simultaneously to return from indicating position back to non-indicating position, substantially as and for the purpose hereinbefore set forth.

In testimony whereof I have signed my name to this specification in the presence of two subscribing witnesses.

JULIUS SAX.
